UNITED STATES PATENT OFFICE

LEON J. CAHN, OF NEW YORK, N. Y.

DESIGN FOR AN ATTACHMENT PLUG RECEPTACLE OR SIMILAR ARTICLE

Application filed November 30, 1931. Serial No. 41,913. Term of patent 3½ years.

To all whom it may concern:

Be it known that LEON J. CAHN, citizen of the United States, and resident of New York city, in the county of New York, and State of New York, has invented a new, original, and ornamental Design for an Attachment Plug Receptacle or Similar Article, of which the following is a specification, reference being had to the accompanying drawing, forming part thereof, in which,

The figure is a perspective view of an attachment plug receptacle, embodying my new design.

I claim:

The ornamental design for an attachment plug receptacle or similar article, substantially as shown.

Dated, November 25, 1931.

LEON J. CAHN.
